UNITED STATES PATENT OFFICE

2,455,242

EMERGENCY DAY AND NIGHT SIGNALING
DEVICEMartin Dwyer, Hewlett Harbor,
Long Island, N.Y.

Application July 21, 1945, Serial No. 606,312

8 Claims. (Cl. 102—37.8)

1

This invention relates to signalling devices and more particularly to smoke and pyrotechnic devices adapted to be carried in emergency life rafts, boats or the like and which may be used in the daytime to produce signalling smoke, or at night to produce signalling light. The invention is a continuation-in-part of my copending applications, Serial No. 487,261, filed May 17, 1943, now Patent No. 2,448,521, and Serial No. 565,672, filed November 29, 1944.

Increasing air transport over large bodies of water has made it extremely important that all crews operating such transports have in their emergency life rafts day and night-time signalling devices capable of expelling large volumes of colored smoke or light-emitting composition. The same situation exists with respect to ships and lifeboats.

One of the principal requirements of such devices or signals is that they remain absolutely watertight and moistureproof until they are used, irrespective of the weather conditions and other environment to which they are exposed prior to such use, because the ignitable contents of the devices must be dry or else they cannot be used effectively, if at all.

Where separate day and night signals are supplied, frequently the particularly useful one of the signals is lost or otherwise unavailable just when it is most needed. A principal object of the invention is to provide a single signalling unit embodying both daytime and nighttime signalling units so that the proper one of the two always is available for use, while the other acts as a handle.

Another of the principal features of the invention relates to novel container constructions for such devices that are of extremely rugged construction, that are absolutely water and moistureproof, i. e., hermetically sealed, and that are capable of keeping the ignitable contents dry even under the severest conditions so that the devices may be used whenever required in an emergency.

Another object of the invention is to produce devices of this character that will be comparatively simple in construction, cheap and easy to assemble.

Another object of the invention is to provide devices of the character described that will be self-contained, each including everything necessary for its operation in an emergency and which may be put into use without requiring any tools.

Another principal object is to provide devices which may be safely held in hand by the user during use without requiring any handle whatsoever.

2

Another object is the provision of signalling devices, each of which is a completely independent entity, so that the loss of one or more will have no effect whatsoever on the ability to use those remaining.

Still a further object of this invention is to provide novel positive means for igniting the desired one of the signalling means associated with the device.

10 To the accomplishment of the foregoing and such other objects as may hereafter appear, this invention consists in the novel construction and arrangement of parts hereinafter to be described and then sought to be defined in the 15 appended claims, reference being had to the accompanying drawing forming a part hereof and which shows, merely for the purposes of illustrative disclosure, preferred embodiments of the invention, it being expressly understood, however, 20 that various changes may be made in practice within the scope of the appended claims without digressing from the inventive idea.

In the drawing, in which similar reference characters denote corresponding parts.

25 Fig. 1 is an isometric view partially cut away of one form of my device.

Fig. 2 is a full end view of the device of Fig. 1, the view being the same for either end; and

30 Figs. 3, 4 and 5 are respective sectional elevations of modified inner container constructions that may replace that shown in Fig. 1.

Referring to the drawing and first to Fig. 1, 35 10 denotes an external casing or container of metal or other suitable material. In the embodiment shown, this casing is of cylindrical form but it may be of any desired form. Its walls may be smooth as shown or have the configuration of my first aforementioned application. A member or spacer 11 of substantially cup-like form and preferably of metal is admeasured to fit within the lower end of the container 10. The bottom portion 11a of this member has reduced diameter and is provided with a central opening 12 to permit rapid escape of products of combustion from the device as will be presently described. This member or spacer 11 forms a positioning guide for other parts of the device as will be presently described.

40 50 A cover member 14 preferably of metal is provided for the member 11. This cover member is admeasured to fit within the upper portion 11b of said member 11 adjoining on the shoulder 11c of the member 11 so that the wall of portion 11b lies between the side walls 14a of the member 14 and the rim portion of container 10. The lower

edges of the member 14 and of the container 10 are beaded over together very securely to provide an annular sealing bead or rib 18. This bead is very secure and is made moisture and leak-proof in any well-known manner, as by the use of solder or the like.

The cover member 14 has a comparatively large opening 16 defined by a shoulder 16a that is normally sealed by a removable tear strip or member 17 also preferably of metal which is secured about said opening in well-known manner as by soldering or the like. This tear strip 17, while removable, effectively and completely seals the opening 16 against moisture, water and gas until it is removed. A ring 18 or other equivalent means is attached to the tear strip 17 to facilitate removal of the latter by the user without tools. It is merely necessary for the user to grasp the ring 18 and pull off the tear strip 17 to expose the opening 16.

The bottom of the container optionally is covered by a removable cardboard cap Z or the like which is readily removed before use to expose the ring 18.

The entire inner wall of the container or casing 10 may be coated with an insulating lining of lacquer or the like that may be applied either by spraying, dipping or in any other suitable manner. This lining preferably has heat-insulating properties.

An inner container 19 of metal or other suitable material for holding a smoke-producing compound C to be presently described is provided. This container 19 has smaller diameter than that of the external casing 10 so that a substantial air space 20 may be provided between the walls of the two containers 10 and 19. The wall of container 19 is completely imperforate as is that of container 10 so that the air in space 20 serves as an effective heat insulator. An insulating liner of cardboard or the like could replace the air space. Any heat insulating medium could be used. Thus, the container 10 may be safely and comfortably held without danger by the user while the compound C in container 19 is burning.

A cover 22 preferably of metal is provided for the lower end of the container 19. This cover has a central opening 23 and a plurality of additional openings 24 arranged about the opening 23 to provide for the escape of the smoke and gases of combustion of the compound C within the container 19 outwardly through said cover. The cover 22 is fitted reentrantly within the bottom of the container 19 and its edge beaded over with the lower edge of said container at 25. The reduced portion 11a of the cup-like member or spacer 11 is admeasured to fit within this cover 22 and thereby serves to center the lower end of inner container 19 with respect to outer container 10.

The inner container 19 is provided with an insulating lining similar to that of container or casing 10 and is filled with the suitable smoke compound C which is capable of producing large volumes of smoke when burned that will be visible as a cloud even in a high wind. The constituents of this smoke compound include a dye for coloring the smoke as desired, a burning agent to produce the smoke and fuel so that a sustained volume of smoke will be produced when the compound is ignited. Any of the commercially known satisfactory smoke-producing compounds may be utilized.

The smoke compound may, for example, consist of a mixture of:

	Percent
Dye	70.23
Sucrose	13.26
Potassium chlorate	14.56
Powdered graphite	1.95
	100

These percentages may be varied because of variations in the character of the chemicals.

The sucrose may be a good commercial grade of confectioners' XXXXX sugar, the polarization of which is not less than 99.9% sucrose. It shall be of such fineness that 100% shall pass a 100 mesh sieve and not more than 20% shall be retained on a 200 mesh sieve.

The potassium chlorate used in the device is preferably at least 99% pure with not more than 5% moisture. It should pass 100% through a 100 mesh screen.

A dye is H. V. Orange B which is a naphthalene-azo-dimethylaniline, paranitrobenzene azo-B-naphthol coupling.

The graphite should be of the same order of fineness and purity as the sucrose and potassium chlorate.

A fuse 27 extends through the compound C and terminates in igniter assembly 28 that has elements which will serve to light the fuse 27. This igniter assembly 28 has a cap member 29 carrying an igniting compound similar to that in safety matches. A pull wire 30 extends through the cap member 29 and the igniting compound. This wire is crimped at 30a and crimped and coated at 30b with match-striking compound. The end 30c of this wire extends through the tear strip 17, its outer end being soldered at 30d to said tear strip in such a way as to seal the opening in the tear strip 17 through which the end has been passed in the assembling of the device. The portion 30a of the wire being crimped does not slip and prevents accidental contact between the coated portion 30b and the igniter compound in cap 29. Since the end of wire 30 is attached directly to the tear strip 17, removal of the tear strip 17 will automatically cause the striker portion 30b to fire the igniter compound in cap 29 and fire the fuse 27. The fuse 27 is secured against withdrawal by the cross pin 32 around which the fuse is looped. This pin is preferably of soft-drawn copper wire or hard aluminum wire or the like. A quick match 31 is attached suitably to the fuse 27. This match is of standard manufacture and preferably is free of sodium nitrate NaNO_3 . It serves to flash fire the compound C.

Spaced-apart washers 33 of paper or other desirable material lie at the top of the compound C and serve to retain it in container 19 and to protect the fuse 27. A similar washer 34 of paper or the like underlying the compound C is provided.

A top 19b preferably of metal is provided for the container 19, being reentrant at 19c and attached at 19d to said container as by beading or the like to insure a leak-proof seal.

A spacer 35 overlies the top 19b. This spacer 35 preferably is of a plastic composition and has a reduced portion 35a that fits within the reentrant portion 19c. The main body of the spacer has a diameter equal approximately to the inner diameter of container 10 and serves as an insulator for purposes presently to be described.

A flare container 40, preferably of metal, is suspended from the upper rim of container 10. The bottom of the container 40 rests upon the spacer 35. This container 40 has a smaller diameter than the inner diameter of the outer container 10 providing the air space 20 which functions similarly to air space 20. A liner or flare tube 42 is fitted within the container 40 resting on a bottom liner 43 of paper or the like and terminating short of the upper edge of the container 40. Preferably, the liner tube 42 is of fiber stock but other materials can be substituted. The tube 42 is filled with a pyrotechnic mix M which is designed to provide a brilliant light visible over long distances at night. Any suitable such mix may be provided, and, for example, may comprise

	Percentages by weight
Potassium chlorate	15
Anhydrous strontium nitrate	45
Magnesium powder (Grade A coated)	21
Hexachlorbenzene	12
Gilsonite	7
	100

Weight per charge, approximately 25 grams. Because of variations in the chemicals the formula may be modified in order to obtain the desired brilliance or burning time.

The top of the mix M is covered with first fire mix N which, for example, may consist of approximately 1 gram of a mixture in percentages by weight of

	Percent
Potassium nitrate	52.75
Antimony trisulphide	21.98
Sulphur	13.19
"A" dust	8.79
Dextrose	3.29
	100.00

"A" dust is a fine dust (200 mesh size) of black powder. Because of variations in chemicals, this formula may be modified in order to obtain the desired speed of ignition.

The quick or first fire mix N and the top of tube 42 are covered by a disk 43' preferably of tissue paper. The disc 43' has a central perforation.

A top support 44 is fitted within the container 40 at its upper end. This support 44 has an annular flange 45 that rests upon and retains the liner 42 within the container 40. A second annular flange 46 of this support has approximately the diameter of the container 40. A tongue 47 integral with the flange 45 extends upwardly at an angle therefrom. This tongue receives and supports an igniter cup 48 whose mouth is directed toward the quick fire mix N. This cup contains a suitable friction igniter composition I of any well-known type, for example, that used on the heads of so-called safety matches.

A pull wire 49 extends through the mix and the head of the cup 48. This wire has a crimped uncoated portion 49a and an additional crimped portion 49b at one end coated with the conventional scratch mix necessary to fire the composition I by friction. The coated portion 49b is positioned to lie clear of the igniter composition I and in the support 44 so that accidental striking cannot occur. The uncrimped portion 49c of the wire 49 extends through the top of the cup 48 for a purpose to be presently described.

A top cover 50 for the outer container is provided. This cover is beaded over together with

the upper edges of container 10 and container 40 to form an annular bead 51 that provides a hermetical seal. The cover 50 has a large central opening defined by an upstanding rim 52. This opening is sealed normally by a tear strip 53 which is secured to said rim 52 about the opening in well-known manner as by soldering or the like. This tear strip, while removable, effectively and completely seals the opening defined by rim 52 against moisture, water and gas until removed. A ring 54 or other equivalent means is attached to the tear strip 53 to facilitate the removal of the latter by the user without tools. It is merely necessary to grasp the ring 54 and pull off the tear strip 53 to break the seal.

The portion 49c of the wire 49 is extended through a small opening in the tear strip and soldered over this opening at 55 to secure it to said tear strip and to seal the said opening. Thus, when the seal is broken and the tear strip is pulled away from the cover, the pull wire 49 is pulled with it drawing its crimped coated portion 49b through the igniting compound I, thereby lighting the latter and starting the burning of mixes N and M to produce the signal light. It is to be noted that the uncoated crimped portion 49a must first be drawn through the compound I. This prevents accidental striking of the compound I, if the tear strip should accidentally become separated from the cover 50 as by falling. In such event, the strip will not be pulled away from the cover sufficiently to draw the coated crimped portion 49b through the igniter I. The uncoated crimped portion 49a will provide sufficient resistance to such movement of the pull wire 49 and thus avoid the danger of accidental ignition of the igniter I. During combustion of the latter, the entire device may be held safely by the user who grasps the container 10. The air space insulations 40 and 20 and the spacer 35 prevent undue heating of the container 10 and permit comfortable safe holding of the device in the user's hand.

If instead of the light flare, it is desired to use the smoke signal, the tear strip 17 is stripped from the cover 15 and pulled away therefrom, thereby automatically drawing striker wire 30 and striking the igniter compound in cap 29 to light the fuse 27, the quick match 31 and the smoke-burning compound C. The container 10 may be safely grasped by the user during combustion of the compound C whose smoke escapes voluminously through openings 24 and 16. The air space 20 provides safe heat insulation for the outer container 10. Also, the plastic spacer 35 prevents the heat of combustion of compound C from fusing the flare mixes M or N.

Thus in the daytime, the smoke compound C can be burned for smoke-signalling purposes, while at night the light or pyrotechnic yielding compound M can be burned to produce a signal light.

The single device described is an entirely self-contained unit whose two compounds C and M may be independently used under the appropriate operating conditions eliminating the necessity for carrying separate types of signals for day and night use, and also reducing the necessary storage space for such devices.

The inner containers 19 and 40 may be replaced by somewhat modified constructions if desired. For example, as shown in Fig. 3, the spacer 35 is eliminated and the closed bottom 40a of the container 40' is formed as a threaded socket 40b covered or surrounded by a suitable

7
insulation lining 40c of porcelain, plaster or other heat insulation medium. Likewise the top 19a of the container 19 is formed as a threaded plug member 19b that may be screwed into the socket 40b. This plug likewise is filled with heat-insulating lining 19c similar to lining 40c. These joined containers 19' and 40' are filled with the same contents as respective inner containers 19 and 40 and carried in an outer container identical with outer container 10. Operation is the same.

In Fig. 4, the abutting closed ends 40a and 19d of containers 40'' and 19'' are joined together by spot welding or the like at 59. Both are lined with suitable heat insulation material similar to that of material 19c and 40c. These joined containers 19'' and 40'' are likewise filled with the same contents as respective inner containers 19 and 40 and are carried in an outer container identical with outer container 10. Operation is the same.

If desired, the separate containers 19 and 40 may be replaced by a single unit 60 separated by a partition 61 into compartments 19''' and 40''' which correspond otherwise with the containers 19 and 40. The opposite sides of the partition are lined with insulating material 19e and 40e similar to that of material 19c and 40c. The two compartments 19''' and 40''' are likewise filled with the same contents as the respective inner containers 19 and 40 and are carried in an outer container like that of container 10. Operation is the same.

While specific embodiments have been described, it will be understood that changes within the scope of the claims is contemplated. There is no intention of limitation to the exact details shown and described.

What is claimed is:

1. In a device of the character described, an outer container, an inner imperforate container for smoke-producing compound or the like, means for exposing and simultaneously igniting the smoke-producing compound through one end of said outer container, a second imperforate inner container within said outer container for flare-producing compound, means for heat insulating the contents of the two inner containers from each other, and means for exposing and simultaneously igniting said flare-producing compound through the other end of said outer container.

2. In a device of the character described, an outer container, an inner imperforate container for smoke-producing compound or the like, means for exposing and simultaneously igniting the smoke-producing compound through one end of said outer container, a second imperforate inner container within said outer container for flare-producing compound, said two inner containers being arranged end to end and each having an open end facing toward opposite ends of the outer container, means for spacing and heat insulating the two inner containers from each other, and means for exposing and simultaneously igniting said flare-producing compound through the other end of said outer container.

3. In a device of the character described, an outer container, an inner imperforate container for smoke-producing compound or the like, means for exposing and simultaneously igniting the smoke-producing compound through one end of said outer container, a second imperforate inner container within said outer container for flare-producing compound, means for exposing and simultaneously igniting said flare-producing compound through the other end of said outer container.

8
tainer, threaded means for joining the two inner containers, and means for heat insulating the contents of said inner containers from each other.

4. In a device of the character described, an outer container, an inner imperforate container for smoke-producing compound or the like, means for exposing and simultaneously igniting the smoke-producing compound through one end of said outer container, a second imperforate inner container within said outer container for flare-producing compound, means for exposing and simultaneously igniting said flare-producing compound through the other end of said outer container, means for joining the two inner containers, and means for heat insulating the contents of said inner containers from each other.

5. In a device of the character described, an outer container, an inner imperforate container for smoke-producing compound or the like, means for exposing and simultaneously igniting the smoke-producing compound through one end of said outer container, a second imperforate inner container within said outer container for flare-producing compound, means for exposing and simultaneously igniting said flare-producing compound through the other end of said outer container, spot-welded means for joining the two inner containers, and means for heat insulating the contents of said inner containers from each other.

6. In a device of the character described, an outer container, an inner imperforate container for smoke-producing compound having a closed end and an open end, the latter facing an end of said outer container, a second inner imperforate container for flare-producing compound also having a closed end and an open end facing the opposite end of the outer container, means for joining the two closed ends of the inner containers, means for heat insulating the contents of the two inner containers from each other, closure means for the opposite ends of the outer container for hermetically sealing its contents, a tear strip for each closure means, and means connected to each tear strip for simultaneously igniting the contents of that inner container exposed by the removal of the respective tear strip.

7. In a device of the character described, an outer container, an imperforate inner container for smoke-producing compound or the like, a second imperforate inner container for flare-producing compound or the like, means for spacing and heat insulating the inner containers from each other, means for heat insulating the inner containers from the outer container, a covering member for each end of the outer container for hermetically sealing the contents of the respective inner containers within said outer containers, independent means removable respectively from each covering member, and means in conjunction with each of said last-named means to automatically ignite the contents of that inner container exposed upon removal of the respective independent means.

8. In a device of the character described, an outer container, an imperforate inner container for smoke-producing compound or the like, a covering member for one end of the outer container, means for centering said inner container within the outer container so as to provide a uniform air space between the side walls of the inner and outer containers, a second imperforate open-ended inner container for receiving flare-producing compound or the like aligned with said first-named inner container, means for spacing and

heat insulating the two inner containers from each other, the open end of said second inner container facing toward the other end of said outer container, a covering member for said other end of said outer container, said two covering members being joined to said outer container to hermetically seal its contents, removable tear strips, one for each covering member, and igniting means in conjunction with each tear strip and secured thereto automatically to ignite the contents of that inner container exposed upon removal of the respective one of the tear strips. 10
